BLACK-OUT CURTAIN DEVICE FOR DOORS
OR SIMILAR OPENINGS

George A. Barker, Washington, D. C.

Application September 2, 1942, Serial No. 456,982

15 Claims. (Cl. 160—114)

(Granted under the act of March 3, 1883, as
amended April 30, 1928; 370 O. G. 757)

The invention described herein may be manufactured and used by or for the Government for governmental purposes, without payment to me of any royalty thereon.

The present invention relates to a blackout curtain device for a door or similar opening in a dwelling, store, restaurant, trailer or anywhere that during a "blackout," entrance or exit is necessary or desirable without the possibility of egress of interior light.

The primary purpose of my invention is to provide a simple and easily installed apparatus that is adaptable for use with any opening or conventional door assembly.

Another object of my invention is to provide a blackout curtain device that does not materially interfere with the passage through the door and which, although the user may be carrying cumbersome packages, may be operated with a minimum physical effort with no possibility of light escaping during the entrance or exit.

A further object of the invention is to provide a blackout curtain device manufactured from readily obtainable and economical materials that may be installed with little effort and without the necessity of employing skilled workmen.

Still another object of the invention is to provide a blackout curtain device that after once installed may be left permanently and when not in use may be quickly moved to a position so as not to interfere with the usual passage through the door or moved to operative position just as quickly.

A still further object of the invention is to provide a blackout curtain device formed primarily of flexible light proof curtains or drapes that are easily moved aside and automatically swing back when in operation and which are capable of being bunched to occupy a minimum of space when not in use.

Other and further objects of the invention will be apparent from a detail description thereof, wherein only a preferred form of embodiment of the invention is shown and described, reference being had to the accompanying drawings, forming a part hereof, in which—

Figure 1 is a view from the interior of a room showing the blackout curtain device installed over a door.

Figure 2 is a horizontal section on the line 2—2 of Figure 1, showing a person entering the blackout curtain device through the open door.

Figure 3 is a similar view showing the progress through the blackout curtain device past the enclosed curtain and before leaving the same.

Figure 4 is a perspective of the guide tracks in which the curtains are hung.

Figure 5 is a vertical section on the line 5—5 of Figure 2 showing the inner or enclosed curtain being swung aside.

Figure 6 is a partial vertical section on the line 6—6 of Figure 2.

Figure 7 is a vertical section on the line 7—7 of Figure 6 with cover plate removed.

Figure 8 is a fragmentary view of the lower edge of the curtain showing the weights therein.

Referring to the drawings there is shown in Figure 1 a complete installation of the blackout curtain device as seen from the interior of a room. The wall 1 has the usual door opening 2 in which is hingedly mounted a door 3. The room is provided with the usual floor 4. Mounted above the door opening is a cover plate 5 wider than the door opening and secured to the under side of the same are a pair of guide tracks 6 and 7 the contour and arrangement of which are best shown in Figures 4 and 6. Slidably mounted in the guide tracks are flexible light proof curtains or drapes 8 and 9 of any desired material and preferably fire-proofed. The guide tracks 6 and 7 are secured to the underside of the cover plate 5 by projecting ears 10 through which pass screws or other suitable fastening means. The outer curtain 8 is carried by the guide track 6 and the enclosed or inner curtain 9 is carried by the guide track 7. The curtains hang to a point touching the floor 4 and are held in position by staggered weights 11 sewed in the folds at the lower edges as shown in Figure 8.

The guide tracks are each formed of inverted U-shaped members with the base lying against the bottom of the cover plate and held in position in a manner formerly described. One leg of the U is bent inwardly and up to form an enclosed track 12. The curtain is mounted with its upper edge enclosed in the guide by bent spaced pins 13 each having a portion 14 lying over and slidable along the track 12 with an extension 15 piercing and supporting the curtain. This assembly is best shown in Figures 6 and 7.

The curtains or drapes 8 and 9 when in operative position extend the full length of the respective guide tracks in which they are mounted. One end or edge 16 of the curtain 8 is secured to the wall 1 adjacent the door opening 2 by suitable fastening means 17. One end or edge 18 of the curtain 9 is secured to the wall 1 at a point spaced from and on the opposite side of the door opening 2 from which the curtain 8 is secured by suitable fastening means 19. This leaves each cur-

tain 8 and 9 with free ends or edges 20 and 21. To retard free sliding of the end curtain supporting pins 13, for a purpose to be hereinafter more fully described, each track 12 is provided adjacent the corresponding free end of the curtain with a notch 22 in which the end pin 13 normally rests as shown in Figure 7.

The curtains or drapes 8 and 9 when in position as a blackout device for the door opening 2 are arranged to be hung at one side thereof in the cover plate carried guide tracks 6 and 7. Their arrangement is best shown in the cross-sectional views of Figures 2 and 3. The curtain 8 forms a bay spaced from but entirely encompassing the opening 2. The enclosed curtain 9 extends across said bay, but does not in itself cover the door opening and partitions the bay into two sections A and B, the first being adjacent the door opening 2. The curtains being light proof with their upper edges enclosed in the guide tracks and their lower edges touching the floor 4 and normally held thereby by the weights 11, will prevent the egress of interior light during a "blackout" when the door 3 is opened.

A person entering the bay section A through the open door 3 first encounters the curtain 9. By moving aside or pulling back the free end or edge 20 of the curtain in a manner shown in Figure 5 he can enter the bay section B as shown in Figure 3. The free edge 20 lies in contact with a portion of the curtain 8 intermediate the ends of the same and is easily swung back. Upon passing this curtain and when fully in the section B the edge 20 automatically swings back to normal contact with the curtain 8 to prevent any passage of light from section A to section B. The person then pushes aside or moves the free end or edge 21 of the curtain 8 from the wall in which it is normally in contact and enters the room. As the curtain 9 blocks off any escape of interior light from the section B, no light can escape from the room upon final entrance. Obviously, the same operation occurs in reverse upon a person leaving the room.

By the operation described the blackout device positively prevents the escape of light as successive movement of the free ends or edges of the curtains is necessary upon entrance or exit and after each movement and before the next the free ends or edges automatically swing back to a position preventing the egress of light. Due to the fact sliding movement of the end curtain carrying pins 13 is retarded by the notch 22 of the track 12 in which they are seated, during the normal movement or swinging back of the curtain edges as shown in Figure 5 the curtain will not slide bodily along the track in the guides so that, when released, will automatically return to position with no further effort. This is especially helpful for persons carrying cumbersome bundles who do not have free use of both hands. This result is due to the fact the curtains are flexible and drape hung and supplemented by the weights at the bottom edge will automatically return to their normal hung position.

This blackout curtain device is very easily installed. It is merely necessary to secure the cover plate above the door opening, run the pin attached curtains 8 and 9 in their respective guide tracks 6 and 7 and secure the edges 16 and 18 to the wall 1. Due to the fact the curtains are of flexible material and drape hung, when not in actual use, they may be easily run along the tracks 12 to a bunched position adjacent the secured edges 16 and 18 where they will be out

of the way and will not interfere with the normal use of the door.

Although I have only described in detail one embodiment of the invention, it will be apparent to those skilled in the art that the invention is not so limited, but that various modifications may be made therein without departing from the spirit thereof or from the scope of the appended claims.

Having described my invention, what I claim as new and wish to secure by Letters Patent is:

1. A blackout curtain device for a door or similar opening comprising a pair of light sealing elements at one side thereof, one of said elements enclosing the other element and normally contacting therewith at one edge.

2. A blackout curtain device for a door or similar opening comprising a pair of longitudinally movable light proof members at one side thereof, one of said members entirely covering the opening and the other enclosed therein and only partially closing the opening.

3. A blackout curtain device for a door or similar opening comprising a pair of longitudinally movable light proof members at one side thereof, one of said members entirely covering the opening and the other enclosed therein and only partially closing the opening, said last mentioned member being normally in free end contact with the enclosing member.

4. A blackout curtain device for a door or similar opening comprising a pair of different sized light proof drapes arranged at one side of the opening with one enclosed within the other, and said drapes being successively longitudinally movable and restorable from one end to seal the opening from light escape during use.

5. A blackout curtain device for a door or similar opening comprising a pair of light proof drapes arranged at one side of the opening with one enclosed within the other, and said drapes being successively longitudinally movable and restorable from opposed ends.

6. A blackout curtain device for a door or similar opening comprising a pair of successively mounted light proof drapes at one side thereof, and said drapes being longitudinally movable and restorable from opposite ends.

7. A blackout curtain device for a door or similar opening comprising a light proof curtain encompassing said opening and bowed therefrom to form an entrance bay, and a second light proof curtain arranged in said bay and extending from adjacent the opening to a point in contact with the first curtain intermediate the ends of the same.

8. A blackout curtain device for a door or similar opening comprising a light proof curtain encompassing said opening and bowed therefrom to form an entrance bay, a second light proof curtain arranged in said bay and extending from adjacent the opening to a point in contact with the first curtain intermediate the ends of the same, opposed ends of said curtains being successively removable and restorable to seal the opening from light escape during use.

9. The combination with a wall having a door or similar opening, a light proof curtain covering said opening and bowed therefrom to form an entrance bay with the ends of said curtain normally in contact with the wall at opposite sides of the opening, and a second light proof curtain enclosed by the first and extending from the wall adjacent the opening to normal contact with the first curtain intermediate the ends of the same.

10. The combination with a wall having a door or similar opening, a light proof curtain covering said opening and bowed therefrom to form an entrance bay, with the ends of said curtain normally in contact with the wall at opposite sides of the opening, a second light proof curtain enclosed by the first and extending from the wall adjacent the opening to normal contact with the first curtain intermediate the ends of the same, and said curtains being so spaced that upon entrance or exit they are successively swung back and restored to prevent egress of interior light.

11. The combination with a wall having a door or similar opening, a light proof curtain covering said opening and bowed therefrom to form an entrance bay with the ends of said curtain normally in contact with the wall at opposite sides of the opening, a second light proof curtain enclosed by the first and extending from the wall adjacent the opening to normal contact with the first curtain intermediate the ends of the same, said curtains being so spaced that upon entrance or exit they are successively swung back and restored to prevent egress of interior light, and mountings for the curtains that permit them to be bunched against the wall at opposite sides of the opening when not in use.

12. The combination with a wall having a door or similar opening, a light proof curtain for said opening bowed therefrom to form an entrance bay with one end of the curtain secured to the wall adjacent one side of the opening and the other end being free but contacting the wall at the other side of the opening, a second light proof curtain enclosed by the first and secured at one end to the wall between the opening and free end of the first mentioned curtain with its other end being free but in contact with the first curtain intermediate the ends of the same, and said

curtains being so mounted and positioned that upon entrance and exit the free ends may be successively swung back and restored.

13. The combination with a wall having a door or similar opening, a light proof curtain for said opening bowed therefrom to form an entrance bay with one end of the curtain secured to the wall adjacent one side of the opening and the other end being free but contacting the wall at the other side of the opening, a second light proof curtain enclosed by the first and secured at one end to the wall between the opening and free end of the first mentioned curtain with its other end being free but in contact with the first curtain intermediate the ends of the same, and said curtains being so mounted and positioned that upon entrance and exit the free ends may be successively swung back and restored, a cover plate extending from the wall above the opening by which the curtains are supported, and said curtains extending the full height of the opening.

14. The combination with a wall having a door or similar opening, a cover plate extending from the wall above the opening, a pair of guide tracks supported thereby, light proof drapes hung in said guides one forming an entrance bay and the other extending across the same, and means to retard sliding of the curtains on the tracks at opposite ends.

15. The combination with a wall having a door or similar opening and a floor, a cover plate extending from the wall above the opening, a pair of guide tracks supported thereby, light proof drapes hung in said guides one forming an entrance bay and the other extending across the same, and weights in the lower edge of said drapes to hold them in contact with the floor.

GEORGE A. BARKER.
